4023

PATENTED MAY 17 1870

United States Patent Office.

JOHN H. BELLAMY, OF CHARLESTOWN, MASSACHUSETTS.

Design No. 4,023, dated May 17, 1870.

DESIGN FOR CLOCK-FRONT.

The Schedule referred to in these Letters Patent and making part of the same

I, JOHN H. BELLAMY, of Charlestown, Middlesex county, Massachusetts, have invented and produced a new and original Design for Clock-Fronts, of which the following is a specification.

The nature of my design is fully represented in the accompanying photographic illustration, to which reference is made; and

It consists of an ornamented clock-front, so arranged and designed as to represent above the dial A a triple crown, B, surmounted by a globe, C, and a cross, D, together with cross-keys E E. Below the dial A is an open book, F, with cross-staves, partial staves G

and shepherds' staves H, the whole to be inclosed in ornamental scroll-work.

What I claim, and desire to secure by Letters Patent, is—

An ornamental clock-front, substantially as shown and described, reference being had to the accompanying photographs and to the letters of reference marked thereon.

JOHN H. BELLAMY.
